PACKAGING CONTAINER FOR A COFFEE MAKER OR THE LIKE

Cornelis van Spronsen, Akron, Ohio, assignor to Stephen
Gould Paper Company, Inc.

Filed Mar. 30, 1973, Ser. No. 346,406

Term of patent 7 years

Int. Cl. D9—03

U.S. Cl. D9—201

FIG. 6

FIG. 7

FIG. 1 is a front perspective view of a packaging container for a coffee maker or the like showing my new design.

FIG. 2 is a side elevational view on a reduced scale, the opposite side being a mirror image of the side shown;

FIG. 3 is a rear elevational view thereof;

FIG. 4 is a top plan view;

FIG. 5 is a bottom plan view;

FIG. 6 is a sectional view on a reduced scale taken on the line 6—6 of FIG. 1; and

FIG. 7 is a front elevational view with the top and bottom trays removed.

I claim:

The ornamental design for a packaging container for a coffee maker or the like, substantially as shown and described.
